UNITED STATES PATENT OFFICE.

ELMER E. MULLINIX, OF BURLINGTON, KANSAS.

OVERSHOE RETAINER.

1,409,060.

Specification of Letters Patent. Patented Mar. 7, 1922.

Application filed August 15, 1921. Serial No. 492,288.

To all whom it may concern:

Be it known that I, ELMER E. MULLINIX, a citizen of the United States, residing at Burlington, in the county of Coffey and 5 State of Kansas, have invented a new and useful Overshoe Retainer, of which the following is a specification.

This invention relates to an attachment for rubber sandals or low overshoes, one of 10 its objects being to provide a novel form of clamp for engaging the heel of a shoe when pressed downwardly into the sandal so that the heel will be tightly gripped, and the sandal will be prevented from becoming 15 detached accidentally.

Another object is to provide an attachment of this character which is light in construction, simple and compact and can be applied readily to a sandal overshoe or, if 20 preferred, can be built thereinto as a part of the overshoe.

With the foregoing and other objects in view which will appear as the description proceeds, the invention resides in the combination and arrangement of parts and in 25 the details of construction hereinafter described and claimed, it being understood that, within the scope of what is claimed, changes in the precise embodiment of the invention shown can be made without departing 30 from the spirit of the invention.

In the accompanying drawings the preferred form of the invention has been shown.

35 In said drawings

Figure 1 is a view partly in side elevation and partly in section of an overshoe or sandal having the present improvements combined therewith, only a part of the overshoe being shown and a portion thereof being broken away, the heel engaging jaws being shown in upstanding positions.

Figure 2 is a section on line 2—2, Figure 1.

40 Figure 3 is a section on line 3—3, Figure 1.

Figure 4 is a section on line 4—4, Figure 3.

Figure 5 is a detail view of one of the 50 latch studs.

Referring to the figures by characters of reference 1 designates a portion of an overshoe or sandal the heel of which has been indicated at 2. A base plate 3 is mounted on 55 the heel within the sandal and may be se-

cured thereto in any manner desired, as by means of short screws 4. The ends of this plate, which lie close to the sides of the overshoe are rolled inwardly to form hollow beads 5 and extending forwardly from the 60 middle portion of the plate 3 is a tongue 6 terminating in an upstanding ear 7. Another ear 8 is extended upwardly from the tongue and is spaced from the ear 7. In this ear 8 is slidably mounted a releasing plunger 65 9 one end of which is slidably mounted in a small opening 10 in the back of the heel portion of the overshoe or sandal while the other end portion has a head 11 thereon against which bears a spring 12 thrusting 70 against the ear 7. Thus the spring serves to hold head 11 pressed normally against ear 8 and with the rear end of the plunger 9 projecting beyond the back of the overshoe.

Projecting rearwardly from the upper 75 corners of the head 11 are beveled studs 13 the lower ends of which form stop shoulders as indicated at 14. Thus these studs will act as latches as will be hereinafter described.

Pivottally mounted at each side of the plate 3 is a heel engaging device, the two devices being oppositely disposed. Each of these devices comprises preferably a single link of stiff spring wire bent to form a yoke 85 15 which overhangs the plate 3, each yoke having one corner portion movable downwardly onto the beveled face of one of the studs 13 so as to shift the studs and the head 11 against the action of spring 12 until 90 said corner portion arrives below the shoulder 14, whereupon the spring 12 will return the studs to their normal positions and the yoke will be fastened down on the plate 3 as shown by dotted lines in Figure 2. The 95 outer ends of both arms of each yoke 15 merge into coils or eyes 16 which are mounted on a pintle extending through one of the beads 5 as shown at 17. From these eyes or coils the wire forming the heel engaging device is extended upwardly and inwardly to form a jaw 18, the terminals of the wire lapping to form the upper portion of the jaw as shown by full and dotted lines in Figures 1 and 4 respectively. A spring 100 strip 19 is extended under the plate 3 and has its ends extending upwardly past the beads 5 and attached to the jaws 18 so as to exert normally an outward pressure against each of said jaws as shown in Figure 2.

110

In the structure shown the jaws 18 and the upwardly extending ends of the spring strip 19 are embedded in the side portions of the overshoe or sandal so that said portions will move with the jaws. Ordinarily the yokes 15 are in their uppermost position as shown in Figure 2 and the jaws 18 are thus spread apart. When a shoe is inserted into the overshoe or sandal the heel, when pressed 10 downwardly, will engage and force down the yokes 15 so that they will snap under the studs or latches 13 and thus be securely held. This action will cause the jaws 18 to swing toward each other and clamp upon the sides 15 of the heel. As the jaws and yokes are formed of stiff spring wire the jaws can yield to any necessary extent during the clamping operation. They will, however, grip the heel of the shoe with sufficient pressure to prevent the overshoe from becoming accidentally detached. When it is desired 20 to remove the overshoe the projecting end of the plunger 9 is pressed against some object so as to cause the studs 13 to move forwardly 25 out of engagement with the yokes 15. Consequently the spring strip 19 will immediately move the jaws 18 apart and the yokes 15 upwardly so that the heel will be released and can be lifted readily from between the jaws 18.

It is to be understood that instead of embedding the jaws 18 in the sides of the overshoe they can be mounted on the inner surfaces of the overshoe so as to swing inwardly

relative thereto during the clamping operation. When the jaws are mounted in this way it becomes possible to apply the attachment to ordinary overshoes or sandals where as the construction first described must be combined with the overshoe during the 40 course of its manufacture.

What is claimed is:—

1. The combination with an overshoe, of opposed jaws in the side portions thereof, inwardly extending members projecting 45 from the jaws and yieldable relative thereto, spring controlled latches within the overshoe, said members being depressible by an inserted shoe to shift the jaws into engagement with the shoe and to engage the latches, 50

2. The combination with an overshoe, of opposed jaws in the side portions thereof, inwardly extending members projecting from the jaws and yieldable relative thereto, spring controlled latches within the overshoe, said members being depressible by an inserted shoe to shift the jaws into engagement with the shoe and to engage the latches, and a releasing plunger connected to the latches. 60

In testimony that I claim the foregoing as my own, I have hereto affixed my signature in the presence of two witnesses.

ELMER E. MULLINIX.
